UNITED STATES PATENT OFFICE.

LEONARD SLIGER, OF INDIANAPOLIS, INDIANA.

CONTAINER FOR OIL CANS.

Application filed February 16, 1925. Serial No. 9,632.

This invention relates to a bracket enclosure for enclosing and supporting an oil can upon a sliding tube musical instrument, such as a trombone and the like.

5 The chief object of the invention is to provide a container that is mountable upon a musical instrument of the character described and which will detachably support and enclose an oil can whereby the musician 10 may open the container, gain access to the oil can, remove the same, oil the tube of the musical instrument and replace the can within the container all with one hand, leaving the other hand free for holding the instrument or manipulating the same. It is 15 apparent that the foregoing is a great convenience for musicians having instruments of the character described when marching in parades or at other times when it is not convenient to carry on the person an oil can and 20 remove the top thereof for oiling purposes.

The chief feature of the invention consists in the mounting of an oil can in a container which will permit the container to be 25 readily detached therefrom and when detached be ready for instant use without the removal of any other additional parts.

The full nature of the invention will be understood from the accompanying drawings 30 and the following description and claim.

In the drawings Fig. 1 is a side elevational view of a trombone showing the invention applied thereto. Fig. 2 is an enlarged top plan view and a portion of the supporting musical instrument and the invention applied thereto. Fig. 3 is a view similar to Fig. 2 with the cover removed. Fig. 4 is a transverse sectional view taken on line 4—4 40 of Fig. 2 and in the direction of the arrows. Fig. 5 is a longitudinal sectional view taken on line 5—5 of Fig. 2 and in the direction of the arrows.

In the drawings 10 indicates a musical instrument having a connecting tube or support 11. A container 12 is suitably secured to said support by means of the clamping construction 13. Herein the clamping construction 13 constitutes a wing integral with the body portion 12 and a detachable wing 113 associated therewith in clamping arrangement. The body 12 is provided with a hingedly supported cover 112 and said cover carries a catch 14 seatable in a recess 15 in the body. Herein a spring 16 is shown in angular relation and fulcrumed to the body portion at 17. The lower portion of the

spring is adapted to engage the underside of an oil can 18 and maintain the oil can in engagement with the cover and thus prevent rattling of the oil can in the container. The other end of the spring 16 carries a latch 19 adapted to engage or cooperate with the catch 14 and lock the cover to the body portion. It will be apparent that when the latch is released from the catch and the cover is opened, the spring 16 will tend to project the oil can 18 outwardly whereupon it may be readily grasped by the fingers. The body portion 12 includes an opening 20 and slidably supported therein is a button 21. This button is depressible to release the latch from the catch by actuating the spring 16.

One end of the body portion 12 carries a projection 25 which is apertured and threaded as at 26. Threaded in said projection is 75 a hollow plug 27 having the central aperture 28 and at its end a head 29. A bearing member or packing 30 is positioned in said central aperture 28 and interposed between the head 29 and said packing is a coil spring 80 31. A nut 32 has a threaded engagement with the threaded exterior of the plug 27 and has a bevel or conical seat portion 33 adapted to cooperate with a collar 34 carried by the oil can 18 and concentric with the 85 stem 35 of said can.

From the foregoing it will be understood that when the can 18 is positioned in the container the end of the can or oiling spout is closed by the packing 30 yieldingly maintained in engagement therewith. The can is retained in substantially rigid relation by the threading of the head 29 which will cause the nut 32 to bear upon the coil 34 thereby sealing this joint and also securing 95 the oil can against movement in the container. When it is desired to remove the oil can the thumb nut 29 is actuated, the finger piece 21 is also actuated and this releases the cover and projects the oil can ready for finger engagement and removal.

The invention claimed is:

A counterweight for a musical instrument including a sliding tube comprising a relatively heavy body portion in the form of a 105 case adjustably supported upon the instrument for counter-balancing purposes and having means therein for supporting a container.

In witness whereof, I have hereunto af- 110 fixed my signature.

LEONARD SLIGER.
